UNITED STATES PATENT OFFICE.

CHARLES M. TALLMAN, OF DELAVAN, WISCONSIN.

PIPE-CLEANER.

1,347,304.

Specification of Letters Patent. Patented July 20, 1920.

Application filed June 17, 1919. Serial No. 304 857.

To all whom it may concern:

Be it known that I, CHARLES M. TALLMAN, a citizen of the United States, residing at Delavan, in the county of Walworth, 5 State of Wisconsin, have invented a new and useful Pipe-Cleaner; and I do hereby declare the following to be a full, clear, and exact description of the invention, such as will enable others skilled in the art to which 10 it appertains to make and use the same.

The invention relates to pipe cleaners and has for its object to provide a pipe cleaner and case therefor which may be carried in a smoker's pocket, thereby providing 15 a cleaner which will always be within easy reach of the smoker and at the same time, by incasing the same prevent the soiling of the pockets and the clothing from becoming odorized by the nicotin from the 20 pipe.

A further object is to provide a cylindrical shaped casing, said casing being provided with a divisional wall therein, which wall is loosely mounted and provided with 25 a right angle arm at its lower end, said divisional wall forming two chambers, one for the pipe cleaner and the other for absorbent cotton to be used during the pipe cleaning operation. Also to provide an 30 aperture in the bottom of the casing into which the pipe cleaner may be inserted to force the divisional wall upwardly so that the cotton within the casing may be removed as desired for use.

With the above and other objects in view the invention resides in the combination and arrangement of parts as hereinafter set forth shown in the drawings, described and claimed, it being understood that changes 35 in the precise embodiment of the invention may be made within the scope of what is claimed without departing from the spirit of the invention.

In the drawings:—

45 Figure 1 is a side elevation of the pipe cleaner and case.

Fig. 2 is a vertical sectional view through the cleaner and case.

Fig. 3 is a horizontal sectional view taken 50 on line 3—3 of Fig. 1.

Referring to the drawings, the numeral 1 designates a cylindrical casing having a chamber 2 therein. The upper end of the casing 1 is flared as at 3 thereby forming 55 a tapered opening 4 for the reception of the handle 5 of the pipe cleaning rod or

probe 6, which probe is adapted to be made of metal of a flexible nature so that the same will easily bend and flex to conform to the curvature of smoke passages of various types of pipes. A closure for the lower end of the casing 1 is formed by means of a spherical member 7, said member being retained in the lower end of the casing 1 by means of the flared and bent 60 portion 8 of the lower end of the casing. The member 7 is provided with an aperture 9 extending through the same.

Chamber 2 of the casing 1 is divided into compartments 10 and 11 by means of a vertically disposed and loosely mounted divisional wall 12, said wall having its lower end bent as at 13 so as to form a right angle portion 14, said right angle portion 14 being so positioned as to overlie the aperture 9, 70 in the spherical member 7 so that when it is desired to raise vertically disposed wall 12, it will only be necessary to insert the member 6 in the apertures 7 and force the same upwardly, which will cause the end of the 75 member 6 to engage the portion 14 and consequently force the divisional wall upwardly. This upward forcing of the divisional wall will cause the absorbent cotton 15 to be raised high enough so that the same 80 may be reached by the operator, thereby allowing the utilization of small pieces of cotton to be wrapped around the end of the pipe cleaning member 6, thereby allowing a thorough cleaning and drying of the smoke 85 passage in a pipe.

It will be seen that by loosely mounting the wall 12, that when the end of the member 6 is forced downwardly into the compartment 10, that the upper end of the divisional wall will move, thereby allowing the proper seating of a handle member 5. From the above it will be seen that a pipe cleaner and casing for the same is provided 95 wherein cleaning cotton may be carried and also one wherein the clothes will not become soiled by the cleaner, nor the odor from the same allowed to penetrate the clothing.

The invention having been set forth what 100 is claimed as new and useful is:—

1. A pipe cleaner and cylindrical case therefor comprising a pipe cleaning probe, said probe having a handle member at one end thereof, said handle member being 110 adapted to be disposed in one end of the cylindrical casing, said cylindrical casing

- being divided longitudinally into compartments, one of said compartments being adapted to receive the pipe probe and the other compartment cleaning material.
- 5 2. A casing for a pipe probe comprising a cylindrical member having a chamber therein, said chamber having a vertical wall therein thereby dividing the chamber into compartments, one of said compartments being adapted to receive the pipe probe, the other compartment being adapted to receive cleaning material, the lower end of the vertical wall being bent so as to underlie the bottom of the cleaning material compartment, and an aperture in the bottom of the cylindrical casing and disposed under the underlying portion of the vertical wall that underlies the cleaning material compartment.
- 10 15 20 3. A casing for a pipe probe comprising a cylindrical member, said cylindrical member having a chamber therein, a partition wall loosely mounted within the chamber thereby forming two compartments, the lower

end of the partition wall being provided 25 with a right angle portion forming a bottom for one of the compartments, the lower end of the cylindrical member being provided with a spherical closure member, said spherical closure member being provided 30 with an aperture disposed below the right angle portion of the loosely mounted partition wall, the upper end of the cylindrical member being flared, said flared end being adapted to receive a handle of a pipe cleaning probe when the probe is forced downwardly into one of the compartments, said loosely mounting of the partition wall allowing the movement of the upper end thereof when the pipe probe is forced into 35 its compartment.

In testimony whereof I have signed my name to this specification in the presence of two subscribing witnesses.

CHARLES M. TALLMAN.
